ALFRED DUVALL, OF BALTIMORE, MARYLAND.

Letters Patent No. 83,941, dated November 10, 1868.

IMPROVEMENT IN ROTARY STEAM-ENGINES.

The Schedule referred to in these Letters Patent and making part of the same.

To all whom it may concern:

Be it known that I, ALFRED DUVALL, of Baltimore, in the county of Baltimore, and State of Maryland, have invented a new and useful Improvement in Rotary-Pressure Engines, to be operated by steam or any other fluid or liquid; and I do hereby declare that the following is a full, clear, and exact description of the construction and operation thereof, reference being had to the accompanying drawings, and letters of reference thereon, making a part of this specification, in which—

Figure 1, plate 1, is a vertical cross-section.

Figure 2, plate 1, a longitudinal section of the springs, bar, and set-screws in the ends of the ellipse.

Figure 3, plate 1, a cross-section of the same.

Figure 4, plate 1, a cross-section of spring pressing against packing-rings.

Figure 5, plate 1, a plan of same.

Figure 6, plate 2, a longitudinal section in elevation.

Figure 7, plate 3, a vertical cross-section, showing the engine with two valves.

To enable others skilled in mechanics to make and use my invention, I will proceed to describe the construction and operation of the same.

The character of my invention, as shown by the accompanying drawings, consists, first, in an elliptic piston, revolving within a cylinder of a true circle, equal in diameter to the length of the ellipse, with one or two, as desired, oscillating and nearly-balanced valves; also, the arrangement of the end packing-rings, and appliances for adjusting the same, and of weakening the points of the elliptic piston, by which they are made elastic, and arrangement for adjusting the same, so as to compensate for wear; and also providing an oil or water-chamber in the ends of the same, and the combinations as shown by the accompanying drawings, as will be more fully described in this specification.

Fig. 1, plate 1, shows an engine with but one valve, and receiving the agent of power at but one point.

Fig. 7, plate 3, shows an engine of a more efficient character, having two valves, and receiving the agent of power at opposite points. When using two valves, the longer points of the valves, pressing on the face of the ellipse, are so proportioned as to close the inlet-ports at the time the exhaust commences through the discharge-ports.

A is the shaft on which the revolving elliptic piston B is fastened.

This piston is of an elliptical form, and has formed within the material composing its outer walls, and at the points of its greatest diameter, chambers D D, which serve as oil-chambers, and at the same time they serve to weaken the piston at the points of its contact with the cylinder, so that by means of the set-screws H, bars G, and springs F, the weakened or elastic portions may be set out and brought into contact with the interior surface of said cylinder.

C is the stationary cylinder in which the elliptic piston revolves.

D D are oil-chambers in the ends of the elliptic piston.

E E are oil-holes for charging the oil-chambers D.

F are round springs in the ends of the ellipse.

G G are bars pressing against the springs F.

H are set-screws let into and pressing on the bars G.

I I are the inner-end packing-rings.

J, gum packing between the packing-rings I and K.

L are conical springs, pressing against the packing-rings K, as shown in figs. 4 and 5, plate 1, and fig. 6, plate 2.

M are set-screws, pressing against the springs L.

N are flange-rings, bolted to the flanges of the cylinder C, and through which the set-screws M work.

O are the stationary shafts, on which the valves P oscillate.

Q are the valve-chambers.

R R, recesses in the backs of the valves P, to be filled with Babbitt metal.

S, recess in valve P, forming an oil-chamber.

T, oil-tube, supplying oil-chamber S.

U, inlet-pipe and port.

V, exhaust-pipe and port.

W, journal-stands, supporting engine-shaft.

X, bed-plate.

Y Y, fly-wheels.

For reversing, I use two engines of the same class, on the same shaft, or connected by couplings, with the necessary stop-valves, &c., so as to operate either engine alternately, thereby giving a reverse motion.

Operation.

The steam or other agent of power, being let on through a valve in the inlet-pipe, presses against the front of the valve P, which forms an abutment, and the front, or part of the valve bearing on the elliptic piston, is made a little longer than the back arm, by which means the valve is constantly kept tight to the face of the elliptic piston during its revolutions. The point of the ellipse being moved a little beyond the inlet-port, the agent of power acts on the same, and causes it to revolve in the direction indicated by the arrows, and, from the momentum of the fly-wheels, a continuous rotary motion is maintained, and the power transmitted from the shaft of the engine as may be desired.

What I claim as my invention, and desire to secure by Letters Patent, is—

1. An elliptical piston, constructed with elastic or yielding surfaces upon its points of greatest diameter, substantially as shown and described.

2. The chambers D D, formed within the piston, substantially as shown and described.

3. The combination of the elliptical piston B, the chambers D D, and the set-screw H, bars G, and springs F, substantially as shown and described.

4. The arrangement of the packing-rings K and I, rubber or elastic packing J, spring L, and set-screw M, substantially as shown and described.

ALFRED DUVALL.
